TOOTHPICK DISPENSER

Jesse J. Solomon, Legion, Tex.

Application November 18, 1947, Serial No. 786,612

1 Claim. (Cl. 312—84)

2

This invention relates to improvements in dispensers for toothpicks, matches and similar small articles, and more particularly to an improved dispenser for storing toothpicks and dispensing them, substantially one at a time, upon manual actuation of the dispenser.

It is among the objects of the invention to provide an improved dispenser which is easy to operate, positive in operation, effective to deliver a single toothpick, or not more than two or three toothpicks, at a time, is easy to load, retains a supply of toothpicks in a sanitary condition, and delivers single toothpicks to a location from which they may be easily removed for use, and which is simple in construction, economical to manufacture and neat and attractive in appearance.

Other objects and advantages will become apparent from a consideration of the following description in conjunction with the accompanying drawing wherein:

Figure 1 is a side elevation of a toothpick dispenser illustrative of the invention;

Figure 2 is a front elevation of the toothpick dispenser illustrated in Figure 1;

Figure 3 is a vertical longitudinal cross-section taken substantially on the line 3—3 of Figure 2; and

Figure 4 is a longitudinal cross-section of a fragmentary lower portion of the dispenser taken substantially on the line 4—4 of Figure 3.

With continued reference to the drawing, the improved dispenser has a pair of side walls 10, a back wall 11 and a front wall 12 inclosing a rectangular upright chamber having a width slightly greater than the length of a conventional toothpick. A top cover 13 is hinged at its rear edge to the upper edge of back wall 11 by a suitable hinge 14 and extends forwardly over the upper end of the chamber resting upon the top edges of the back side and front walls. This cover may be raised, when desired, for access to the interior of the upper end of the chamber to place a supply of toothpicks in the storage compartment provided in the upper portion of the chamber.

The front wall 12 has its lower edge 15 positioned a considerable distance above the bottom of the chamber and a base or bottom wall 16 is secured to the bottom edges of the back and side walls and extends forwardly of the plane of the front wall 12. The side walls are provided at their lower ends with forwardly direction extensions 17 which extend along the base 16 to a location near the front edge thereof and have upwardly and rearwardly inclined top edges which

extend from a position somewhat above the front edge of the base to the bottom edge 15 of the front wall 12, as is clearly illustrated in Figures 1 and 3. A low, forwardly and upwardly inclined, wall 18 extends along the front edge portion of the base 16 between the forward ends of the side wall extensions 17 and a movable inclined cover 19 is pivotally connected at its upper edge by a hinge 20 to the lower edge portion of the front wall 12 and rests upon the inclined upper edges of the side wall extensions. This cover has a downwardly and rearwardly inclined wall 21 secured to its underside at the front edge thereof the lower edge of which rests upon the top edge of the wall 18 when the cover is closed, as illustrated in Figure 3. A tongue 22 extends outwardly from the front or lower edge of the inclined cover 19 at the center thereof, as is clearly illustrated in Figure 2, to provide a convenient lift for the cover so that access may be conveniently had to the space between the side wall extensions and below the cover 19 when desired.

A pair of downwardly and inwardly inclined baffles 23 and 24 are secured in the chamber intermediate the height thereof and constitute a bottom for the toothpick storage compartment in the upper portion of the chamber.

The baffle 24 is secured to the back wall 11 and the baffle 23 is secured to the front wall 12 and extends rearwardly of and below the bottom edge of the baffle 24. The two baffles converge to the transverse center of the chamber between the front and back walls thereof and the convergent edge portions are spaced apart a distance which is normally insufficient to permit the passage of a toothpick therebetween.

A cylindrical roller 25 is positioned immediately below the bottom edge of baffle 23 and has reduced cylindrical end portions 26 and 27 journaled in suitable apertures provided in the side walls 10, as is clearly illustrated in Figure 4. This cylindrical roller has three longitudinal grooves 28 therein which are preferably spaced at equal angular distances around the outer surface thereof and are of a size to normally receive a single toothpick. The roller is positioned so that it contacts the lower edge of the baffle 23, as shown in Figure 3 and normally holds this edge of the baffle in a position relative to the opposed lower edge of the baffle 24 such that a toothpick cannot pass between the lower convergent edges of the two baffles. However, when the lower edges of baffle 23 drops into one of the grooves 28 the baffles are sufficiently separated to permit a toothpick to pass therebetween and the flexible baffle

23 is slightly jarred to cause a toothpick to pass between the convergent edges of the baffles and fall into the upper groove 38 in the roller 25.

A hand knob 29 is secured on the longer reduced end portion 27 of the roller in a manner such that the roller is constrained to turn with the hand knob, and an apertured reinforcing plate 30, secured to the adjacent side wall, also rotatably receives the longer reduced end portion 27 of the roller to provide additional bearing surface for the end of the roller to which the hand knob is attached.

Toothpicks dropping into the grooves 28 of the roller 25 are dropped by the roller, upon continued rotation thereof, upon the upper end portion of an inclined plate 31 which extends from the inner lower edge of wall 18 to the inner surface of back wall 11 at a position above the base 16 and substantially at the level of the roller 25. Toothpicks deposited upon the upper portion of the inclined plate 31 slide down this inclined plate and onto a pair of spaced ramps 32 which position the toothpick at the inner upper edge of wall 18 and above the lower edge portion of inclined plate 31 so that the toothpick can be easily grasped by the fingers of a person desiring to remove the toothpick from the dispenser. This grasping of the toothpick is facilitated by the provision of a recess 33 in wall 18 between the ramps 32. A tongue 34 extending from wall 21 closes the recess 33 when the cover 19 is closed.

The entire dispenser is preferably formed of a suitable translucent or transparent material such as a suitable synthetic resin but some of the parts, such as the hand knob 29 and the tongue 34, may be colored, if desired.

The upper portion of the chamber between the baffles 23 and 24 and the hinged cover 19 provides storage space for a large quantity of toothpicks and maintains the toothpicks in a sanitary condition. As the toothpicks are dispensed by the roller 25 they fall to the ramps 32 where they are protected by the inclined cover 19 so that, if any toothpicks accumulate on the ramps, they are also maintained in a clean and sanitary condition until used.

The base 16 is preferably extended beyond the side walls 10 and is provided in this extended portion with suitable apertures through which screws, or other fastening devices, may be extended to 50 secure the dispenser solidly to a counter or table or, by means of which rubber suction cups 35 may be secured to the base to mount the dispenser upon a smooth surface.

As is apparent from the drawing, the device is 55 extremely simple in construction, positive in operation and is easily operated to dispense toothpicks, substantially one at a time, whenever desired.

The invention may be embodied in other specific forms without departing from the spirit or essential characteristics thereof. The present embodiment is therefore, to be considered in all respects as illustrative and not restrictive, the scope of the invention being indicated by the appended claim rather than by the foregoing description, and all changes which come within the meaning and range of equivalency of the claim are therefore intended to be embraced therein.

What is claimed is:

In a toothpick dispenser having a front wall, a back wall and two side walls defining an upright chamber, a pair of downwardly and inwardly inclined baffles in said chamber secured one to said front wall and one to said back wall and converging to the transverse center of said chamber between said front and back walls, one of said baffles being disposed at its lower edge below the lower edge of the other baffle and being movable relative to said other baffle to open and close between the contiguous portions of said baffles a passage having a maximum width only sufficient to admit one toothpick at a time therethrough, a roller extending transversely of said chamber in contact with the lower edge of said one baffle and journaled in said side walls, said roller having therein longitudinally extending grooves angularly spaced around said roller and having a width and depth slightly greater than the thickness of a toothpick to be dispensed, said passage being closed when the lower edge of said one baffle contacts said roller between said grooves and being opened when the lower edge of said one baffle is disposed in one of said grooves, means secured to said roller at the outer side of one of said side walls for manually rotating said roller, and means below said roller for conveying toothpicks to a location at which they are removed from the dispenser.
